WINDOW CLEANER

Harry L. Sowers, Arcadia, Ind., assignor to Productive Inventions, Inc., Gary, Ind., a corporation of Indiana

Application August 21, 1934, Serial No. 740,815

3 Claims. (Cl. 15—105)

This invention relates to window cleaners and its general object is to provide a cleaning device that is not only capable of use in washing and wiping glass and the like, but will remove all 5 foreign matter therefrom without scratching the same, in minimum time, with minimum effort.

An extremely important object of the invention is to provide a window cleaner that includes an abrasive material such, for example, as a fibrous metallic wool therein as a cleaning element, and which is so arranged with a polishing element that the glass is polished as it is cleaned.

Another object of the invention is to provide 15 a window cleaner of the character set forth, that is simple in construction, inexpensive to manufacture and extremely efficient in use and service.

This invention also consists in certain other 20 features of construction and in the combination and arrangement of the several parts, to be hereinafter fully described, illustrated in the accompanying drawing and specifically pointed out in the appended claims.

In describing my invention in detail, reference 25 will be had to the accompanying drawing wherein like characters denote like or corresponding parts throughout the several views, and in which:

Figure 1 is a perspective view of the window 30 cleaner that forms the subject matter of the present invention.

Figure 2 is a detail view illustrating the application of the metallic wool with respect to the felt head of the device.

Figure 3 is a sectional view taken transversely 35 through the device.

Figure 4 is a fragmentary sectional view through a portion of the device, illustrating a slightly modified arrangement of certain of the elements embodied in the present invention.

40 Referring to the drawing in detail, the reference numeral 1 indicates the body member of my window cleaner, and which as shown is substantially rectangular in shape and relatively narrow. The body also acts in the capacity as 45 the handle for the device and one longitudinal edge thereof is provided with a groove 2 which is relatively shallow and extends the full length of the body, as will be apparent upon inspection of Figure 1.

50 Arranged in the groove 2 and secured therein by any well known means such as adhesive material is a strip 3 of absorbent material such, for example, as felt or the like that is co-extensive with the body 1 and is of the same width thereof as best shown in Figure 3, so that the portions

of the felt extend beyond the groove 2 and the strip is not only secured in the groove but to the entire longitudinal edge.

The strip of felt has arranged longitudinally therein a groove or recess 4 that terminates inwardly of the ends of the felt as shown in Figure 1 and mounted in the groove 4 as well as secured therein by adhesive material is a strip 5 of metallic wool. The strip 3 is likewise provided with apertures 6 that extend through the 10 entire thickness thereof and communicate with the ends of the groove 4 so as to receive right angle bent end portions 7 formed on the ends of the strip of metallic wool as clearly shown in Figure 5, it being apparent that the portions 7 15 are also fixed within the apertures 6 by adhesive material. The outer face of the strip 5 of metallic wool may extend beyond the outer face of the strip 3 of felt, as illustrated in Fig. 4, or the faces may be flush with each other as shown in Figure 3, as well as flat, but in any event the wool is embedded within the felt so that these 20 two elements cooperate in cleaning and polishing glass.

The sides of the body 1 are tapered toward the 25 opposite longitudinal edge thereof as best shown in Figure 3, and the last mentioned edge has disposed therein a groove 8 that extends through the ends of the body and has converging recesses 9 in the bottom thereof.

The groove 8 and recesses 9 are adapted to receive a strip of rubber 10 that has its outer edge beveled as shown, while its inner edge is provided with converging tongues 11 to fit the converging recesses 9. The strip 10 and its tongues 30 are fixed within the groove 8 and recesses 9 by adhesive material. It will be understood that the strip 10 is designed primarily for wiping glass after the latter has been washed and cleaned by the felt and wool.

40 From the above description and disclosure of the drawing, it will be obvious that I have provided a window cleaning device that is capable of removing all foreign matter from glass in an easy and expeditious manner with very little effort without scratching the glass, and this action is accomplished through the instrumentality of the metallic wool which has disposed for co-operation therewith felt in cleaning and polishing the glass, but the important feature of the device is the metallic wool, as it is capable of removing dirt and other foreign matter with very little effort, and which cannot be removed by the use of washing or other cleaning elements without strenuous efforts on the part of the user.

55

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

- 10 1. A window cleaning device comprising a handle body member having a groove formed therein, a strip of absorbent material having a longitudinally extending recess in an exposed side thereof and secured in said groove of the body member, and a strip of abrasive material secured in said recess and having an exposed face portion adjacent the surface of said exposed side of said absorbent material.
- 15 2. A window cleaning device comprising a handle body member having a groove formed therein, a strip of absorbent material having a longitudinally extending recess in an exposed side

thereof and secured in the groove of said body member, and a strip of abrasive material comprising a plurality of elongated fibers secured in said recess and having a face portion exposed for use and adjacent the surface of said exposed side of said absorbent material.

3. A window cleaning device comprising a body member having an edge portion with a longitudinally extending groove therein, a strip of absorbent material having a longitudinally extending recess in an exposed side thereof and secured in the groove of said body member, said strip of absorbent material having an aperture opening into said recess adjacent each end thereof, and a strip of fibrous abrasive material positioned in said recess and extending longitudinally thereof, said strip of abrasive material having a face portion exposed for use and adjacent the surface of said exposed side of said absorbent material and having its end portions extending into said apertures.

HARRY L. SOWERS.
